Primary Examiner — Steven J Czyz

(57) **CLAIM**

The ornamental design for a storage rack, as shown and described.

DESCRIPTION

FIG. 1 is a front, top perspective view of a storage rack, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an exploded view of the storage rack;

FIG. 10 is a perspective view of the storage rack, shown in a state of use with environment; and,

FIG. 11 is another perspective view of the storage rack, shown in a state of use with environment.

The broken lines are shown for the purpose of illustrating both parts of the storage rack as well as environmental subject matter. None of the broken lines form part of the claimed design.

1 Claim, 11 Drawing Sheets
